A. H. FLECK.
BOBBIN HOLDER.
APPLICATION FILED DEC. 17, 1920.

1,397,927.

Patented Nov. 22, 1921.

Albert H. Fleck
inventor

By Godb, Billman & *attorney*

UNITED STATES PATENT OFFICE.

ALBERT HENRY FLECK, OF LAKEWOOD, OHIO.

BOBBIN-HOLDER.

1,397,927.

Specification of Letters Patent.

Patented Nov. 22, 1921.

Application filed December 17, 1920. Serial No. 431,457.

To all whom it may concern:

Be it known that I, ALBERT HENRY FLECK, a citizen of the United States, residing at Lakewood, in the county of Cuyahoga and 5 State of Ohio, have invented certain new and useful Improvements in Bobbin-Holders, of which the following is a specification.

My invention relates to improvements in bobbin holders or supports, the present embodiment of the invention being particularly designed and adapted for use in receiving and supporting the conical shaped tubes or shells commonly known as "cop-tubes" carrying the cops of thread or yarn used in 15 connection with various forms and types of knitting, sewing and looping machines.

The primary object of the invention is to provide a generally improved holder or support of this class, which will be exceedingly 20 simple in construction, cheap of manufacture and efficient in use.

A further and very important object is the provision of an improved support adapted to be readily attached to or detached 25 from the ordinary base plate and spindle used in connection with knitting machines, and when so mounted and attached is adapted to receive the parts and interlock with the base portion of the cop-tube whereby the 30 latter will be securely supported and retained as the thread or yarn is taken from the top of the cop and cop-tube.

With the above mentioned and other ends in view, the invention consists in the novel 35 construction, arrangement and combination of parts, hereinafter described, illustrated in one of its embodiments in the accompanying drawings, and particularly pointed out in the appended claims.

Referring to the drawings, forming a part 40 of this specification, Figure 1 is a view partly in side elevation and partly in section of a holder or support applied to an ordinary cop-tube and to the conventional form 45 of cop-tube support or base plate and spindle.

Fig. 2, a cross sectional view of the same taken on line 2—2 of Fig. 1.

Fig. 3, a perspective view of the improved spindle receiving and clamping screw for attaching the support to the ordinary cop-tube receiving spindle.

Similar numerals of reference designate like parts throughout all the figures of the drawings.

55 The improved holder or support is adapt-

ed to be used in connection with any suitable and convenient bobbin or tube spindle 1, and supporting base 2, and arm or supporting rod 3. In the present instance, the cop-tube receiving spindle 1, and supporting base 2, 60 and arm 3, are of the conventional form frequently used in connection with knitting machines.

In adapting the device for use in connection with the conventional forms or devices 65 above referred to, and particularly in connection with the conventional form of cop-tube 4, usually made of compressed paper or suitable composition, the support 5, is preferably of truncated cone shape spun up from 70 suitable metal forming the inclined side walls and terminating at its top in a supporting head 5^a, the latter being provided with a central opening formed by struck out portions providing an annular flange 5^b. The 75 opening formed by the struck out flange 5^b, is adapted to receive the top portion of the spindle 1, and as a means of securely fastening the support 5 upon the spindle 1, the interior portion of the opening or flange 5^b, is 80 provided with threads adapted to receive a spindle receiving and clamping device consisting, in the present instance, of a sleeve screw 6, embodying the angular shaped head and provided with exteriorly threaded 85 tongues 6^a, the latter being preferably tapered on their outer sides, as shown most clearly in Fig. 3 of the drawings, whereby upon drawing the same downwardly or from left to right in the threaded opening and 90 about the spindle 1, the latter will become firmly clamped to securely support the cop-tube holder 5, upon the spindle 1.

As a convenient means of removably attaching the cop-tube 4, upon or detaching 95 the same from the inverted cup shaped support 5, when the latter is attached to the spindle 1, as above referred to, the inclined sides of the support 5, are preferably provided with corrugations 5^c, arranged in 100 spiral or thread form, said corrugations being preferably formed out of the side walls of the support, as shown, whereby to securely receive and interlock with the inner surfaces of the base portion of the cop-tube, as shown 105 most clearly in Fig. 1 of the drawings.

By virtue of the construction of the holder or support 5, as above described, it will be obvious that the surfaces of irregularly made cones or cop-tubes 4, will assume a perfectly 110

conical shape when threaded or seated upon the support through the medium of the corrugated threads 5°.

Having thus described one of the embodiments of my invention, without having attempted to set forth all the forms in which it may be made, or all the modes of its use, what I claim and desire to secure by Letters Patent, is,—

- 10 1. In a cop-tube support, a conical-shaped cop-tube support shaped to receive and engage within the base portion of the cop-tube and provided with threaded cop-tube engaging corrugations and terminating at its top in a tapered threaded opening provided with a tapered clamping screw to receive and clamp the cop-tube spindle.
- 15 2. In a cop-tube support, a truncated cone-shaped cop-tube support to receive the base portion of a cop-tube and provided with threaded corrugations, said support terminating at its top in an attaching head having a threaded opening, and a split clamping screw in said threaded opening to receive and clamp a cop-tube spindle.

3. In a cop-tube support, a supporting arm, a supporting base thereon, a spindle on said base, a threaded cone-shaped support provided with a supporting head having a threaded opening surrounding said spindle, 30 and a sleeve clamping screw surrounding said spindle in said threaded opening in co-operative relation to said threaded cop-tube support.

4. In a cop-tube support, a main supporting arm terminating in a supporting disk, a central spindle on the latter extending upwardly therefrom, a threaded tubular support provided at its top with a supporting head having a central threaded opening, and 35 a sleeve clamping screw receiving said central spindle and provided with threaded clamping tongues arranged in said threaded opening of said supporting head and surrounding and clamping said spindle in co-operative relation to said threaded cop-tube support.

In testimony whereof I have affixed my signature.

ALBERT HENRY FLECK.
